UNITED STATES PATENT OFFICE

129,408

DESIGN FOR A CABINET FOR BATTERY CHARGER

Soren L. Christie, Los Angeles, Calif.

Application February 14, 1941, Serial No. 99,012

Term of patent 3½ years

To all whom it may concern:

Be it known that I, Soren L. Christie, a citizen of the United States, residing in Los Angeles, in the county of Los Angeles and State of California, have invented a new, original, and ornamental Design for a Cabinet for Battery Charger, of which the following is a specification, reference being had to the accompanying drawing, forming part thereof.

Fig. 1 is a front perspective view of a cabinet for battery charger embodying my new design; and

Fig. 2 is a rear perspective view thereof.

I claim:

The ornamental design for a cabinet for battery charger, as shown.

SOREN L. CHRISTIE.
